* cited by examiner

Primary Examiner — Sheryl Lane*Assistant Examiner* — Nicole Shiflet(74) Attorney, Agent, or Firm — Raj Abhyanker, P.C.(57) CLAIM

The ornamental design for a display screen or portion thereof with graphical user interface, as shown and described.

DESCRIPTION

The FIGURE is a front view of a display screen or portion thereof with graphical user interface.

The broken lines showing a display screen or a portion thereof are included for the purpose of illustrating environmental structure and these broken lines form no part of the claimed design.
